UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed June 6, 1928. Serial No. 283,204.

The invention relates to improvements in railway draft riggings.

In railway practice, a frequent source of trouble has been found in the inability to maintain the coupler in proper horizontal condition to aline truly with the shock absorbing mechanism of the railway draft rigging. This is especially true where gears of relatively long travel are employed, for example, wherein the travel in buff is greater than in draft.

The main object of my invention is to overcome the objections pointed out by providing a slidable supporting member for the coupler shank which supports the shank for the greater portion of its length and especially at a point closely adjacent the coupler head or horn and wherein the slide also provides a support for the front main follower which cooperates with the shock absorbing mechanism.

A further object of the invention is to provide, in a railway draft rigging including a horizontal yoke member, in combination with a sliding coupler support of the character indicated means for supporting the side arms of the horizontal yoke to thereby further assure proper alinement of the parts.

Other objects of the invention will more fully and clearly appear from the description and claims hereinafter following.

In the drawing, forming a part of this specification, Fig. 1 is a longitudinal, vertical, sectional view through the underframe structure of a railway car, at one end thereof, illustrating my improvements in connection therewith. Fig. 2 is a horizontal, longitudinal, sectional view corresponding substantially to the line 2—2 of Fig. 1. And Figs. 3 and 4 are vertical, transverse, sectional views corresponding respectively to the lines 3—3 and 4—4 of Fig. 1.

In said drawing, 10—10 indicate the usual channel shaped center or draft sills of a railway car underframe, having a yoke member 12 disposed therebetween, the yoke member being of the horizontal type and having spaced side arms provided with the usual coupler key receiving slots at the forward ends thereof. A shock absorbing mechanism of

any well known type is disposed within the yoke. In the present instance, the shock absorbing mechanism is illustrated as of the friction type and comprises the usual friction shell 13 having friction shoes and a wedge member cooperating therewith. The shock absorbing means is supported by a saddle plate 14 secured to the bottom flanges of the draft sills. A coupler of well known form is employed in connection with my improved railway draft rigging and the same is designated by 15. The coupler is provided with the usual shank which abuts a front follower 16 disposed within the yoke and cooperating with the wedge member of the friction shock absorbing mechanism. The coupler shank is anchored to the yoke member by the usual coupler key 17 which extends transversely of the shank and has its opposite ends disposed within the slots of the side arms of the yoke.

In carrying out my invention, I provide a combined striking casting and supporting member A and a cooperating coupler carrying slide B.

The combined striking casting and supporting member A is in the form of a hollow box-like member having spaced vertical disposed side walls 18—18, and horizontally disposed spaced top and bottom walls 19—19. The casting is open at the opposite ends, as clearly shown in Figs. 1 and 2, and has the side walls provided with laterally projecting vertical flanges 20—20 at the outer end thereof, the flanges 20 overhanging the front end portions of the draft sills 10.

The top wall 19 of the casting A is provided with a vertical extension 21 at the forward end thereof forming the striking member which cooperates with the inner edge of the coupler head or horn. Inwardly of the member 21 the top wall of the casting A is provided with a transverse web 22 which is secured to the angle end sill 23 of the car underframe structure.

The bottom wall of the casting A is provided with raised sections 24—24 at the opposite sides thereof forming horizontal guide ledges on which the arms of the yoke member ride. The depressed portion of the bot-

tom wall 19 between the portions 24 forms a guide member for the coupler-carrying slide B. As clearly shown in Fig. 1, the bottom wall 19 of the casting A is shorter than the top wall and is reinforced by transverse webs 25-25. The top wall 19 of the casting A is reinforced by a longitudinally extending central web 26. Adjacent the inner end, the casting A is provided with a transverse web 27 formed integral with the web 26 and reinforced by a horizontal section 28. The web 27 forms the upper transverse front stop of the railway draft rigging, with which the front follower 16 cooperates. The raised sections 24 of the bottom wall terminate in alignment with the web 27 and the end faces thereof of form stops 29 which act as front limiting stop lugs cooperating with the follower 16.

The side walls 18 of the casting A are provided with horizontally disposed slots 30-30 which are adapted to accommodate the coupler key 17 for sliding movement. The slots 30 are reinforced by flanges surrounding the same, the flanges being seated in longitudinal openings 31 provided in the vertical webs of the draft sills. The openings 31 are open at the forward end, as indicated in Fig. 1, to permit assembling of the casting A with the draft sills, the casting being inserted between the draft sills inwardly of the underframe structure.

The carrier member or slide B is also in the form of a casting provided with a horizontal bottom wall 32 which rides directly on the bottom wall 19 of the casting A. At the forward end, the bottom wall 32 is upwardly offset, as indicated at 33 to provide a relatively wide supporting ledge which engages the bottom side of the coupler shank adjacent the coupler head. The wall section 33 is reinforced by a transverse front end wall section 34 and longitudinally disposed side wall sections 35-35. The wall section 32 is also reinforced by longitudinally extending vertically disposed side flanges 36-36 and a central web 37. The flanges 36 and central web 37 are of such height that the upper edges thereof are below the top face of the wall 33. At the inner end, the casting B is provided with downwardly extending transversely disposed spaced flanges 38 and 39 connected by side wall sections. The flange 38 cooperates with the inner web 25 to limit the outward movement of the slide B. Rearwardly of the connecting end wall of the carrier slide B, the same is provided with a horizontal ledge 40 which directly supports the front main follower of the draft rigging. At the inner end, immediately in front of the ledge 40, the slide has a transverse rib 41 forming abutment means for the follower 16, whereby when the follower moves outwardly, the slide is returned to normal position. The rib 41 also acts to limit outward movement of the follower when movement of the slide is

arrested by engagement of the flange 38 with the innermost rib 25. The slide B is of such width as to fit freely within the guideway formed between the raised side sections 24 of the casting. At the forward end, the slide is guided between inwardly extending flanges 42 on the casting A. The inner end of the slide is provided with laterally extending lugs 43-43 which engage beneath the lower flanges of the sills 10, thereby guiding the slide and preventing upward tilting of the same.

In the present instance, my improvements are illustrated in connection with a railway draft rigging having a longer stroke in buff than in draft, the slots 30 in the side walls of the casting A being of such length as to permit the necessary greater inward than outward movement of the coupler key.

As clearly illustrated in Fig. 1, the supporting coupler carrying slide B is of such length as to form a support for the greater portion of the length of the coupler shank and also provide a support for the front main follower of the railway draft rigging, whereby the alignment of the coupler shank and the front main follower is at all times maintained, thus assuring proper alignment of the parts with the shock absorbing means of the railway draft rigging. Inasmuch as the coupler shank is supported closely adjacent the coupler head by the member B the shank rearwardly of said support overbalances the head and as the inner end of the shank abuts the wall 28 of the casting A, rocking movement of the coupler shank and drooping of the coupler head is prevented.

The operation of my improved railway draft rigging, during a buffing action, is as follows: The coupler 15 is carried inwardly, thereby forcing the front main follower 16 inwardly also against the friction shock absorbing mechanism 13. Due to the friction between the parts there will be a tendency of the slide B to move inwardly with the coupler shank, thus maintaining the front main follower in supporting relation with the slide. In case there is slippage between the coupler shank and the slide B, the slide will be positively moved inwardly by engagement of the coupler head therewith before the front main follower is disengaged from the supporting ledge 40. Inward movement of the coupler will finally be limited by engagement of the horn thereof with the striking face 21 of the striking casting. When the buffing force is reduced, the expansive action of the shock absorbing means restores the front follower 16 to its normal position and the follower in turn carries the coupler supporting slide B outwardly until its movement is arrested by engagement of the flange 38 with the web 25 on the bottom wall of the combined striking casting and supporting member A.

When a draft or pulling action is applied to the coupler 15, the yoke 12 will be carried outwardly therewith through the medium of the connecting coupler key, thereby compressing the friction shock absorbing mechanism 13 between the inner end of the yoke and the front main follower 16, the follower 16 being held against outward movement by the stop shoulders of the striking casting.

10 I have herein shown and described what I now consider the preferred manner of carrying out my invention, but the same is merely illustrative and I contemplate all changes and modifications that come within the scope 15 of the claims appended hereto.

I claim:

1. In a draft rigging for railway cars, the combination with a coupler having a shank member; of a yoke having a keyed connection 20 with the shank of the coupler; a fixed support on the car; a main front follower within the yoke; a slide movably guided on said support and engaging and supporting the coupler shank outwardly of the keyed connection 25 thereof with the yoke, said slide being movable lengthwise of the mechanism with respect to the yoke; and means on the inner end of the slide for supporting said front follower.

30 2. In a draft rigging for railway cars, the combination with a coupler having a shank member; of a horizontal yoke having a keyed connection with the coupler shank; a support at the end of the car; a slide guided for longitudinal movement on said support, said slide engaging and supporting the coupler shank outwardly of the keyed connection thereof with the yoke; a front main follower within the yoke, said follower being supported on the 35 inner end of said slide, said slide being movable inwardly of the yoke; abutment means on the slide engaged by said follower for moving said slide outwardly in unison with said follower; and stop means on the car for 40 limiting outward movement of the slide.

3. In a draft rigging for railway cars having spaced draft sills, the combination with a casting fixed between said draft sills at the end of the car, said casting having a bottom 45 wall; of a supporting slide guided for movement lengthwise on said bottom wall; a yoke movable with respect to said slide; a coupler provided with a shank member having a keyed connection with the yoke, said coupler shank member being supported on the slide outwardly of the keyed connection thereof with the yoke; and a horizontal top guide wall on said casting engaging and overhanging the top face of the butt end of the coupler shank in all operative positions thereof.

4. In a draft rigging for railway cars, the combination with a front stop casting having a supporting bottom wall and a transverse upper stop shoulder; of a slide guided lengthwise on said bottom wall, said slide having a

transverse stop shoulder at the inner end thereof; interengaging means on said slide and casting for arresting outward movement of the slide when the stop shoulder thereof is in vertical alignment with the transverse stop shoulder of the casting; a yoke with respect to which said slide is movable; a coupler having a shank member connected to the yoke, said coupler shank being supported by said slide outwardly of the connection of the coupler shank and yoke; and a forwardly extending horizontal ledge forming a part of said stop shoulder of the casting and engaging the upper side of the butt end of the coupler shank in all operative positions thereof.

5. In a draft rigging for railway cars, the combination with draft sills; of a yoke member interposed between the sills; a coupler having a shank; means for connecting the coupler shank to the yoke to effect movement of the yoke with the coupler in draft and permit relative movement of the coupler and yoke in buff; supporting means fixed to the car; and a movable slide guided for movement on said supporting means and interposed between said supporting means and the coupler shank for supporting the latter, said slide normally projecting outwardly beyond said supporting means and having lateral extensions at the inner end slidably engaging the draft sills from beneath.

In witness that I claim the foregoing I have hereunto subscribed my name this 29th day of May, 1928.
